[57] CLAIM

The ornamental design for a motorcycle, as shown and described.

DESCRIPTION

FIG. 1 is a front elevation view of a motorcycle showing our new design;

FIG. 2 is a rear elevation view thereof;

FIG. 3 is an elevation view of the left side thereof;

FIG. 4 is an elevation view of the right side thereof;

FIG. 5 is a top plan view thereof; and

FIG. 6 is a perspective view thereof.

The broken line showing of the engine is for illustrative purposes only and forms no part of the claimed design.

FIG. 1.

FIG. 2.

FIG. 3.

FIG. 4.

FIG. 5.

FIG. 6.
